UNITED STATES PATENT OFFICE

PAUL H. MEYER, OF BELLEWOOD, ILLINOIS, ASSIGNOR TO SOLAR-STURGES MFG. CO.,
OF BELLEWOOD, ILLINOIS, A CORPORATION OF ILLINOIS

RECEPTACLE

Application filed September 25, 1931. Serial No. 565,043.

This invention relates to a receptacle for waste products of any kind and one that is particularly adapted for accommodation within doors since it offers facilities for placing material therein and for removing the accumulated material without displacement of any of the surfaces of the receptacle that may be in contact with the walls or objects in the room. It is especially adapted for use in environments where quietness is desired in that the hinged door normally closing the opening provided for the disposition of the material is automatically and silently returned to a closing position on removal of the slight pressure required to open it.

It is an object of this invention to provide a receptacle that by virtue of having no moving or movable parts or projections on the sides or back thereof may be placed solid against the wall or against the walls of a corner or the walls of a recess or that may be built into the wall.

It is another object of this invention to provide a receptacle which may have material inserted therein and material removed therefrom without moving the receptacle from its allotted position.

It is a further object of this invention to provide a convenient method for the removal of the contents of the receptacle without disturbing its position.

It is a still further object of this invention to provide a receptacle having a normally closed entrance that can be opened by slight pressure for the deposit of material and that will be automatically and silently closed upon the removal of the pressure.

It is yet another object of this invention to provide a receptacle that presents a neat substantial appearance, that is simple of construction and economical to manufacture, and that is sanitary in its operation.

Other and further important objects of this invention will be apparent from the disclosures in the specification and the accompanying drawing.

The invention in a preferred form is illustrated in the drawing and hereinafter more fully described.

On the drawing:

Figure 1 is a front elevational view of the improved receptacle.

Figure 2 is a top plan view of the receptacle in position in a corner, the walls being in section and the floor and walls partly broken away. The dotted lines denote the waste can of the receptacle pulled out in emptying position.

Figure 3 is a longitudinal vertical section taken on the line III—III of Figure 1 showing in dotted lines the waste pan pulled out for emptying and the swinging door pushed in for depositing material.

Figure 4 is a transverse sectional view taken on the line IV—IV of Figure 3.

Figure 5 is a fragmentary perspective view of the gravitational balancer of the entrance closure with parts broken away to show the adjusting means.

As shown on the drawing:

The reference numeral 1 denotes a vertically-oblong rectangular case or box resting on legs 2 and having oppositely disposed side walls 3 and 4 and a rear wall 5, all connected to a suitable bottom 6. The upper ends of the side walls are beveled or cut away at the front and an integral cover or top wall 7 is bent downwardly at 8 in association with the side walls.

A front wall or panel 9 of the case is also a front wall of a waste can 10 adapted to fit in the enclosure formed by the case walls and to occupy substantially all of the lower portion thereof. This pan is hinged on its front lower edge at 11 so that it may be swung forward, as indicated by dotted lines in Figures 3, giving access to its open top without removal from the case, a transverse member 11^a engaging the rear wall of the pan to limit the forward movement.

The front panel 9 of the waste can 10 projects beyond the side walls thereof so as to overlap the side walls 3 and 4 of the case 1 as shown at 12 and 12^a in Figure 4, and thus an unbroken front is presented to view. The side walls of the waste can 10 are cut away or beveled slightly from front to back to enable them to clear the top member 11^a as the pan is tilted. Hooks 13 are provided in each corner of the waste can on which a can-

vas bag or other convenient means for receiving and subsequently removing the waste material may be hung.

The cover of the case 7 is provided with a rectangular opening 14 in which a door or closure 15, pivoted at 16 to the cover, swings freely. This swinging door 15 has a flange 17 normal thereto on which a weight is adjustably secured by means of bolts engaging in the slots 19. By these adjusting means, the weight may be so positioned as to cause the door 15 to assume a normal position in the plane of the inclined portion of the cover 7.

In the operation of this receptacle, it is customary, as has been mentioned, to hang a canvas bag or a net or some kind of a receiver suitable for enclosing the waste material on the inside of the waste can. A slight pressure of the hand on the door 15 causes it to swing inward and material deposited in the opening drops into the bag or the like lining the waste can 10. When the pressure is removed the weight 18 causes the door 15 to move back into position for closing the opening 14, and the advantage of having the door 15 swing freely in the opening is that the door comes to rest at its proper position absolutely noiselessly. When the material has accumulated sufficiently the waste can 10 is pulled forward on its hinged edge and the bag is removed and emptied and replaced in the can which is then returned to position within the receptacle.

It will thus be seen that I have invented a new and improved receptacle for waste material which is adapted to be filled and emptied without disturbance of surrounding walls or objects and which is operative when the receptacle is approachable from the front side only.

It will, of course, be understood that many details of construction may be varied through a wide range without departing from the principles of this invention and it is therefore not proposed to limit the patent granted hereon otherwise than necessitated by the scope of the prior art and the appended claims.

I claim as my invention:

1. In combination, a receptacle having two oppositely disposed side walls, a back wall, a bottom wall and a top wall connecting said side walls, a waste can adapted to fit in and substantially occupy the lower portion of said receptacle, and a front wall of said waste can including marginal flanges completely concealing the front edges of the side walls and the bottom wall, and adapted to form the front wall of said receptacle.

2. In combination, a receptacle having two oppositely disposed side walls, a back wall, a bottom wall, and a top wall connecting said side walls, and a waste can adapted to fit in and substantially occupy the lower portion

of said receptacle and hinged to said receptacle at its lower front end, said waste can comprising a front wall adapted to form the front wall of said receptacle, said front wall including marginal flanges extending over and completely concealing the front edges of the side walls and the bottom wall.

3. The combination with a receptacle having an open front side of a waste can adapted to fit in the lower part of said receptacle and hinged thereto at its lower front end whereby said waste can may be inclined forward for emptying, a front wall of said waste can adapted to close the front side of said receptacle and an integral cover on said receptacle, said front wall including side flanges extending entirely over and concealing the front edges of the side walls.

4. The combination with a receptacle of a cover having an opening therein, a door swinging in said opening, an inwardly projecting flange on said door, said flange having a plurality of spaced slots therethrough and a weight disposed adjacent said flange and bolts in said weight passing through said slots for adjustably securing said weight to said flange whereby said door is retained in balanced alignment with said cover.

5. The combination with a receptacle of a cover having an opening therein, a door hinged to said cover for swinging movement through said opening, an inwardly projecting flange on said door disposed perpendicular thereto, said flange having a plurality of spaced slots therethrough, a counterweight for said door comprising a laterally extending bar, and means passing through said slots and secured to said bar for adjustably mounting said bar on said flange whereby said door is retained in balanced alignment with said cover.

In testimony whereof I have hereunto subscribed my name at Bellewood, Cook County, Illinois.
